Bamberg-Friedenau, a German company

Application July 18, 1934, Serial No. 736,111
In Germany July 19, 1933

15 Claims. (Cl. 308—9)

This invention relates to bearings and more especially to means for eliminating pressure and consequent friction in bearings, more particularly in the case of compasses.

The invention and its aims and objects will be readily understood from the following description, taken in connection with the accompanying drawing of one embodiment of the invention herein given for illustrative purposes, the true scope of 10 the invention being more particularly pointed out in the appended claims.

In the drawing, in which the invention is illustratively shown in its application to compasses, more particularly to dry compasses,

15 Fig. 1 is a vertical, central section of a compass embodying one illustrative form of the invention;

Fig. 2 is a vertical central section similar but at right angles to that of Fig. 1;

20 Figs. 3 and 4 are sectional details of the controlling cylinder on lines 3—3 and 4—4 respectively of Fig. 1.

25 Referring to the drawing, in which only so much of known structure is shown as is necessary to the understanding of the present invention, the magnet system of the compass comprises magnets 2 and 4 which herein are shown as very powerful and heavy. Said magnets are carried by a transverse U-shaped member 6, which may carry the usual compass card (not shown) and is provided 30 with a horizontal surface secured to the upper end surface of a controlling piston 8 adapted to work in a cylinder 10, it being so fitted therein that it works without friction. Within the wall of such cylinder there is provided a preferably 35 annular chamber 12 to which compressed air or other pressure fluid is supplied through an intake nozzle 13 from any suitable source of supply (not shown).

40 Said annular chamber 12 communicates with the interior 14 of said cylinder through a plurality of ports, at least three such ports 16 being herein provided, equally spaced circumferentially of the inner wall of said chamber. Said piston 8 will preferably be hollow and provided upon its 45 outer surface with a circumferential channel 18 (Fig. 2) which communicates with the interior 20 of said piston 8 and thence with the interior 14 of said cylinder through a plurality of lateral ports 22 which are equally spaced from each 50 other circumferentially of said piston, at least three of such ports being herein provided. Within the lateral wall of said cylinder 10 there will preferably be provided two diametrically opposed 55 sages 24, 26 which communicate on the one hand

through ports 28 and 30 with the interior of said cylinder and on the other hand with outlet nozzles 32 and 34 for the escape of the compressed air collected in the interior of said cylinder.

The construction so far described operates as follows: The piston 8 with its magnet system tends to sink by gravity, so that ports 16 open fully into said circumferential channel 18. Compressed air entering by said intake nozzle 13 will penetrate to the interior of said cylinder 10 through 10 said ports 16, circumferential channel 18 and ports 22. The cross sectional opening of ports 28 and 30 is herein smaller than the sum of the cross sectional opening of all of ports 16, so that the pressure in the interior of cylinder 10 will increase 15 and cause piston 8 to move upwardly, carrying with it said magnet system, until the lower edge of said circumferential channel 18 obstructs more or less the ports 16, thus diminishing the entrance 20 of air to said cylinder with the result that eventually a state of equilibrium will be established at which the piston 8 and the magnet system carried thereby will float in space, so to speak, due to the air pressure within the interior of said cylinder and which supports the piston. 25

As the compressed air enters the circumferential channel 18 through more than two ports 16 which are symmetrically positioned circumferentially of the lateral wall of the cylinder, and leaves said channel through ports 22 that also are equally spaced from each other circumferentially of said cylinder, an annular air cushion will be formed between the inner wall of said cylinder and its piston which prevents contact between the piston and cylinder wall, thus providing a perfectly frictionless journaling or bearing. Said air cushion also exerts a centering action serving to center said piston within said cylinder. 35

Owing to the considerable masses supported 40 in the bearing, the magnet system might be subjected to vertical vibrations or oscillations, which would injuriously affect the operation of the apparatus as thereby the adjustment of the compressed air controlling ports would be continuously impaired. The invention therefore 45 contemplates the provision of suitable means to overcome this difficulty. Said means herein illustratively comprises suitable damping means which may conveniently include a dash-pot consisting of a cylinder 36 secured at its closed end in the top plate 38 of the casing of the apparatus and in which works a damping piston 40 connected to the controlling piston 8 by a rod 42. 50

The above described centering action of said 55

compressed air cushion between the piston 8 and cylinder wall operates effectively when the apparatus is in vertical position, but possible less so if its position should not be vertical. To meet 5 the latter case the invention therefore contemplates the provision of additional centering means. Herein said means may illustratively comprise bearings of agate or the like, two such bearings 44 and 46 being herein provided which 10 are mounted, respectively, in the top plate 38 and base of cylinder 10 and which surround a resilient spindle 48 extending axially through said controlling piston 8. Said additional centering means in no way interferes with the cushioning and centering action of said compressed air cushion, all lateral shocks being taken up by the latter and the controlling piston 8 rather than by said agate bearings. The latter can 15 therefore be made very light and with sharp contact edges, so that their operation is practically frictionless. The center of gravity of the entire magnet system will preferably be located between the bearings 44 and 46 and preferably at about the level of said piston 8.

20 25 Compasses and particularly dry compasses are often used to indicate the direction in which a ship or air craft is to be steered, or to operate automatic steering means. In the former case angular deviation of the magnet system relatively to the compass casing releases or renders effective a force or system of forces to actuate a direction indicator hand, while in the latter case such angular deviation actuates a relay which renders the automatic steering mechanism operative. With the present invention the escaping compressed air may be used advantageously for either of these purposes. As an illustrative manner and means for accomplishing this result, the lower edge of said controlling piston 8, for example, may be cut away throughout one half of its circumference to form two controlling shoulders 50 and 52 which, on rotation of said piston 8 control the passage of compressed air through the ports 28 and 30. If said 30 piston 8 be rotated clockwise, for example (see Fig. 4) the opening of port 30 will be increased while that of port 28 will be diminished, and vice versa. The pressure ratio of the outlet or exhaust ports 24 and 26 will be correspondingly 35 varied and may be used in a well known manner to render said steering direction indicator or said relay above referred to operative as will be readily understood without further description by those skilled in the art. Means may be provided to adjust the direction indicator or the automatic steering mechanism for a determined course, said means herein illustratively comprising the arrangement whereby said cylinder 10 is mounted for rotary movement in the housing 38, 54, rotation thereof being conveniently effected by a worm 56 carried by a shaft 58 and meshing with a worm gear 60 provided circumferentially of the lower edge of said cylinder.

The stronger the magnets of a compass 40 45 stronger will be its directional force. In the case of dry compasses particularly however the extent to which such directional force can be increased is limited, because every increase in the weight of the magnet system entails an increase 50 in friction in the bearing. The present invention meets this difficulty fully by eliminating the bearing friction and for the same reason enables a stabilizing gyroscope to be added to the magnet system so as to eliminate the oscillations to 55 which magnet systems are liable. This is a re-

sult heretofore impossible of realization in practice owing to the increase in weight and consequent increase in bearing friction entailed. The use of pressure means, such as fluid pressure to eliminate pressure and consequent friction in the 5 bearings is consequently extremely advantageous. This is particularly the case where, as in the illustrative embodiment of the invention above described the weight of the magnet system itself is availed of suitably to regulate in 10 each case the pressure necessary to maintain the magnet system practically in suspense free from friction. Means have been described for this purpose, said means in the illustrative embodiment of the invention shown being accomplished by making the bearing for the magnet system in the form of an equalizing cylinder having a control piston, the latter carrying the magnet system (and the gyroscope where the latter is used) and regulating or adjusting the supply and/or escape of the pressure fluid. Another advantage of the invention resides in the fact that the pressure fluid used to support the magnet system may also be used to drive the gyroscope. Movement of the piston in starting 20 25 may also be used for other purposes, for example to release the gyroscope. Other possible uses and advantages will suggest themselves to those skilled in the art.

I am aware that the present invention may be 30 embodied in other specific forms without departing from the spirit or essential attributes of said invention, and it is therefore desired that the present embodiment of the invention be considered in all respects as illustrated and not restrictive, reference being had to the appended claims rather than to the foregoing description to indicate the scope of the invention.

I claim:

1. A compass comprising, in combination, a 40 cylinder; a hollow, substantially cylindrical piston mounted for rotary and sliding movement in said cylinder; a magnet system carried by said piston; means to permit the entrance of pressure fluid into said cylinder and its exit therefrom; and 45 ports controlled by movement of said piston relatively to said cylinder to vary the supply of pressure fluid admitted to said cylinder and its exit therefrom, and to cause the pressure fluid in said cylinder to support said piston for frictionless movement in said cylinder.

2. A compass comprising, in combination, a cylinder; a hollow, substantially cylindrical piston adapted to rotate and slide in said cylinder; a magnet system carried by said piston; pressure fluid admission ports in the wall of said cylinder, said ports being equally spaced from each other circumferentially of said cylinder; a circumferential channel provided in the outer surface of said piston and having therein a plurality of ports equally spaced from each other, to co-operate with said ports in the cylinder wall and control the admission of pressure fluid through the wall of said piston into said cylinder by movement of said piston relatively to said cylinder.

3. A compass comprising, in combination, a cylinder; a hollow piston adapted to rotate in said cylinder; a magnet system carried by said piston; pressure fluid intake ports in the cylinder and through the piston wall to admit pressure fluid into said cylinder; and fluid pressure outlet ports in the wall of said cylinder and controlled by relative rotary movement of said piston and cylinder.

4. A magnet compass comprising, in combination, a cylinder; a piston free to rotate and slide longitudinally in said cylinder; a magnet system carried by said piston; means to supply fluid to said cylinder; and automatic means controlling the supply of fluid in proportion to the sliding movement of said piston in said cylinder.

5. A magnet compass comprising, in combination, a cylinder; a piston free to rotate and slide longitudinally in said cylinder; said piston being of smaller diameter than the bore of said cylinder to prevent contact with the same; a magnet system carried by said piston; means to supply fluid to said cylinder; an automatic valve means controlling the supply of fluid in proportion to the sliding movement of said piston in said cylinder.

6. A magnet compass comprising, in combination, a cylinder; a piston free to rotate and slide in said cylinder; said piston being of a smaller diameter than the bore of said cylinder to prevent contact with the same; centering means for said piston; a magnet system carried by said piston; means to supply fluid to said cylinder; and means controlling the supply of fluid in proportion to the sliding movement of said piston in said cylinder.

7. A magnet compass comprising, in combination, a cylinder; a piston free to rotate and slide in said cylinder, said piston being of smaller diameter than the bore of said cylinder to prevent contact with the same; a magnet system carried by said piston; and means to supply fluid to said cylinder, including intake ports in the wall of said cylinder and control surfaces on the piston cooperating with said intake ports to control the supply of fluid in proportion to the sliding movement of said piston in said cylinder.

8. A magnet compass comprising, in combination, a cylinder; a piston free to rotate and slide in said cylinder, said piston being of a smaller diameter than the bore of said cylinder to prevent contact with the same; centering means for said piston; a magnet system carried by said piston; means to supply fluid to said cylinder; intake ports in the wall of said cylinder; and control surfaces on the piston cooperating with said intake ports to control the supply of fluid in proportion to the sliding movement of said piston in said cylinder.

50 9. A magnet compass comprising, in combination, a cylinder; a piston free to rotate and slide in said cylinder; said piston being of smaller diameter than the bore of said cylinder to prevent contact with the same; a magnet system carried by said piston; means to supply fluid to said cylinder; means controlling the supply of fluid in proportion to the sliding movement of said piston in said cylinder; and damping means responsive to sliding movement of the piston.

60 10. A magnet compass comprising, in combination, a cylinder; a piston free to rotate and slide in said cylinder, said piston being of smaller diameter than the bore of said cylinder to prevent contact with the same; centering means for said piston; a magnet system carried by said piston; means to supply fluid to said cylinder; means controlling the supply of fluid in proportion to the sliding movement of said piston in

said cylinder; and damping means responsive to sliding movement of the piston.

11. A magnet compass comprising, in combination, a cylinder; a piston free to rotate and slide in said cylinder, said piston being of smaller diameter than the bore of said cylinder to prevent contact with the same; a magnet system carried by said piston; means to supply fluid to said cylinder; intake ports in the wall of said cylinder; control surfaces on the piston cooperating with said intake ports to control the supply of fluid in response to the sliding movement of said piston in said cylinder; and damping means responsive to sliding movements of said piston.

12. A magnet compass comprising, in combination, a cylinder; a piston free to rotate and slide in said cylinder, said piston being of a smaller diameter than the bore of said cylinder to prevent contact with the same; centering means for said piston; a magnet system carried by said piston; means to supply fluid to said cylinder; fluid passages in the wall of said cylinder; means to manually rotate said cylinder; ports in said cylinder; and control surfaces on said piston cooperating with said ports and controlling the flow of fluid in response to the angular movement of said piston in said cylinder.

13. A magnet compass comprising, in combination, a cylinder; a piston free to rotate and slide in said cylinder, said piston being of a smaller diameter than the bore of said cylinder to prevent contact with the same; centering means for said piston; a magnet system carried by said piston; means to supply fluid to said cylinder; fluid passages in the wall of said cylinder; means to manually rotate said cylinder; ports in said cylinder; control surfaces on said piston cooperating with said ports and controlling the flow of fluid in response to the angular movement of said piston in said cylinder; and damping means responsive to sliding movement of said piston.

14. A compass comprising, in combination, a cylinder; a piston adapted to rotate and slide in said cylinder; a magnet system carried by said piston; pressure fluid admission ports in the wall of said cylinder, said ports being equally spaced from each other circumferentially of said cylinder; and a circumferential channel provided in the outer surface of said piston and having therein a plurality of ports equally spaced from each other to cooperate with said ports in the cylinder wall and control the admission of pressure fluid through the wall of said piston into said cylinder by movement of said piston relatively to said cylinder.

55 15. In combination with a compass of the class described, a vertical casing having a closed lower end and an open upper end; means for delivering a pressure fluid into the casing and to discharge it therefrom; a supporting member mounted in the casing for both rotary and vertical sliding movement; a magnet system carried by said supporting member; and valve means associated with said supporting member automatically controlling the supply of fluid to the casing in proportion to the movement of said supporting member.

WALDEMAR MÖLLER.
